UNITED STATES PATENT OFFICE.

LILLUS A. KELLEY, OF CALISTOGA, CALIFORNIA.

DESIGN FOR AN INCANDESCENT-LAMP SHADE.

48,157.

Specification for Design.

Patented Nov. 16, 1915.

Application filed June 15, 1915. Serial No. 34,297. Term of patent 3½ years.

To all whom it may concern:

Be it known that I, LILLUS A. KELLEY, a citizen of the United States, residing at Calistoga, in the county of Napa and State of California, have invented a new, original, and ornamental Design for an Incandescent-Lamp Shade, of which the following is a specification, reference being had to the accompanying drawing, forming part thereof.

The figure is a perspective view of an incandescent lamp shade showing my design.

I claim:

The ornamental design for an incandescent lamp shade, as shown.

LILLUS A. KELLEY.

Witnesses:

C. W. CROUCH,
S. G. CROUCH.
